United States Patent Office

Des. 202,642
Patented Oct. 26, 1965

202,642

WATCH HOLDER

Theodore Frost, Westport, Conn., assignor to Bright Star Industries, Inc., Clifton, N.J., a corporation of Delaware

Filed Nov. 19, 1964, Ser. No. 82,691

Term of patent 14 years

(Cl. D42—8)

FIG. 1

FIG. 2

FIG. 3

FIG. 4

FIG. 5

FIG. 6

FIG. 7

FIG. 1 is a front elevational view of a watch holder showing my new design;

FIG. 2 is a side elevational view thereof;

FIG. 3 is a rear elevational view thereof;

FIG. 4 is another rear view thereof but showing the cover flap in open condition and the hanging flap in closed condition;

FIG. 5 is an inverted rear view thereof showing the cover flap in closed condition and the hanging flap in open condition;

FIG. 6 is a front elevational view of FIG. 5; and

FIG. 7 is a side elevational view of FIG. 5.

The broken-line showing of a watch is for illustrative purposes only.

I claim:

The ornamental design for a watch holder, as shown and described.
